UNITED STATES PATENT OFFICE.

CHARLES D. McDONALD, OF CHICAGO, ILLINOIS, ASSIGNOR TO McDONALD MACHINE CO.,
OF CHICAGO, ILLINOIS, A CORPORATION OF ILLINOIS.

METAL-SHEARING MACHINE.

1,227,162.

Specification of Letters Patent. Patented May 22, 1917.

Application filed July 12, 1916. Serial No. 108,841.

To all whom it may concern:

Be it known that I, CHARLES D. McDONALD, a citizen of the United States, residing at Chicago, in the county of Cook and State of Illinois, have invented certain new and useful Improvements in Metal-Shearing Machines, of which the following is a specification.

The present invention relates to a machine for shearing a lithographed sheet of metal into a plurality of elongated scroll-edged blanks, which are subsequently fed into a die-press for the purpose of having can tops, bottle tops, etc., with a lithographed design therein, stamped therefrom.

One object of the invention is to provide means for centering these lithographed sheets of metal in a position on the machine of the present invention which will correspond to the position which the said sheets occupied when they were placed in the lithographing press, thereby enabling the sheets to be cut into elongated blanks with the lithographed portions occurring in proper position thereon.

A further object of the invention is to feed the said sheets into position to be operated upon by the shearing dies of the present machine in such manner as to maintain them in the centered position in which they were placed prior to the feeding operation.

A further object of the invention is to provide means for trimming the sides of the sheets as they are being fed through the machine.

A further object of the invention is to provide a plurality of centering members against which the work is abutted prior to the feeding operation. These centering members are so arranged as to position the work when abutted thereagainst in the same centered position in which it was placed when secured in the lithographing press.

A further object of the invention is to move one of these centering members out of position prior to the feeding operation, whereby the work is not deflected out of its centered position by engagement with the centering member.

A further object of the invention is to grip and hold the centered work in centered position until it is brought into position to be engaged by the feeding mechanism.

A further object of the invention is to provide means for advancing the work,

after it has been centered, into position to be engaged by the feeding mechanism, and to further provide means whereby this initial advancing or carrying means may be held from operation if the user is not ready to have the work advanced to the feeding mechanism.

The invention further consists in the features of construction and combination of parts hereinafter described and claimed.

In the drawings:

Figure 1 is a plan view of a machine constructed in accordance with the teachings of the present invention;

Fig. 2, an enlarged plan view of the rear or feeding end of the machine;

Fig. 3, a vertical section through the machine of the present invention;

Fig. 4, a section on line 4-4 of Fig. 2;

Fig. 5, a detail section along line 5-5 of Fig. 4, and showing the sliding head for the shearing dies;

Fig. 6, a detail showing the means for driving the cutting disks and feed rolls;

Fig. 7, a section on a somewhat enlarged scale on line 7-7 of Fig. 4;

Fig. 8, a bottom view of the means for shifting one of the centering members to move it out of the way as the work advances toward the feeding means; and

Fig. 9, a sectional detail through the carrier for the movable centering member and the means for causing the movement of said member.

As stated, the present invention relates to a machine or mechanism for severing a sheet of metal having designs or figures lithographed thereon into a series of scroll-edged blanks, which are subsequently fed into a die-press, and can tops, bottle tops, etc., formed therefrom. It is, of course, essential that the final product coming from the die-press shall have the lithographed portion in proper position thereon, and hence it is necessary that such sheets of metal be so cut as to bring the proper lithographed portions at the proper points upon said blanks.

Therefore, it is necessary previous to the cutting operation to center the work in the same position it was centered when the lithographing operation was performed, so that the cutting dies are striking in registration with the arrangement of designs placed upon the work by the lithographing opera-

tion. Owing to variations in the size of these blanks, it is necessary to trim the sides thereof before the shearing operation, and to perform this trimming operation while the work is maintained in a position corresponding to the position it was held in during the lithographing process.

The above-named objects are capable of being carried out by means of the mechanism which is to be described. The machine shown in the drawings for illustrating the present invention comprises a base 9. Upon this base 9 is mounted a table 10, to the front end of which is secured a head 11 formed with suitable guideways, in which travels the movable shearing die 12. This shearing die coöperates with a stationary shearing die 13 and the two dies coöperate to sever the work into scroll-edge blanks. The shearing mechanism and its associated parts are fully shown and described in the patent of C. D. McDonald and C. E. Ennes, No. 1,194,728, issued August 15, 1916, for metal shearing machines. A detailed description of this mechanism is therefore not deemed necessary in the present application, and it is thought sufficient to say that the work is fed to the shearing dies by means of reciprocating feed bars 14, thereby moving it in a step by step movement toward said dies, and that the work is centered with respect to the shearing mechanism by giving it an additional movement at the end of each feeding stroke by means of reciprocating centering members 15. The foregoing is fully described in the McDonald and Ennes patent above referred to.

The features of the present invention are positioned at the rear or receiving end of the machine, and comprise mechanisms for placing the work in the same position it was placed in the lithographing press, and means for carrying the work forward after such centering operation and for trimming the side edges of the work during said forward movement.

Referring now to the means for placing the work in the same position it assumed in the lithographing press, said means comprise two fingers 16, positioned on a carrying plate 17 and adjustable back and forth on said plate by means of a slot and bolt connection 18 (see Fig. 2) with said plate. These fingers 16 are in a position corresponding to the position of certain centering members on a lithographing press. A third centering member 19 is provided, which lies along one side edge of the work and in a position corresponding to the position of a third centering member on a lithographing press. This centering member 19 is shiftable in nature and is intended to be moved out of the way when the work is advanced after having been placed against the centering members 16 and 19.

There are thus three members provided against which the work is abutted to center it, such three members corresponding in position to three members on the lithographing press, and hence when the work is abutting the members 16 and 19, it is centered in the precise position it was centered in the lithographing press. After being so centered, it is necessary to carry the work forward in this centered position until it is engaged by the feeding mechanism; and for holding it during this carrying movement spring clips 20 are provided, carried by the plate 17.

The carrying movement is produced by causing the carrying plate 17 to travel toward feed rollers 21. This plate 17 is secured to a sliding member 22, which travels within guides 23 and is pulled toward the feed rolls 21 by means of a spring 24. The plate 17 is returned to normal position by means of a cam 25 operating against a roller 26 on a pivoted arm 27, which is connected by a link 28 to a lug or ear 29 depending from the member 22. The point where the cam 25 changes from its high part to its low part is indicated by the numeral 30 in Fig. 4. It will be seen that the change from the high to low part is abrupt, giving the arm 27 a quick release for inward movement. The tension exerted by the spring 24 causes the plate 22, together with the link 28 and arm 27, to all move so as to carry the plate 17 toward the feed rolls 21 as soon as the roller 26 passes off from the high part of the cam 25. Thus, the work held to the plate 17 by the spring clips 20 is carried forward to the feed rolls 21. The grip of the clips 20 is sufficiently strong to hold the work to the plate 17, but is not strong enough to interfere with the action of the feed rolls 21 in feeding the work forward. This cam 25 is carried by a shaft 31, which is driven by means of a sprocket 32 and a chain 33. The chain 33 is driven by a sprocket 34 on a shaft 35, and upon this shaft 35 is secured a sprocket 36 driven by a chain 37, which chain is driven by a sprocket 38 on a shaft 39, to which shaft is attached a gear 40 meshing with a gear 41 on a main driving shaft 42, although other suitable means for driving these parts may be employed.

Also mounted upon the shaft 31 and driven thereby is a cam 43 having a short high part 44 arranged to engage a roller 45 upon a member 46, which member is provided with a slot 47, so that it straddles the shaft 31. This member 46 is formed with a head 48 at its upper end, which head seats within a recess 49 in the under face of the plate 22, and the head is maintained normally upward by a spring 48a.

By referring now to Fig. 4, it will be seen that at the time the low part of the

cam 25 is opposite the roller 26, the high part of the cam 43 will be in engagement with the roller 45, thereby depressing the member 46 and pulling the head 48 out from the recess 49, so that the plate 22 is free to move forward when the arm 27 is released and the spring 24 allowed to act to so pull the plate.

The reason for this locking device is that it may sometimes happen that the workmen will not wish to allow the sheet of work to be carried forward at the time when the plate 22 would move. If such is the case, then by holding on to the bar 17 until after the high part 44 of the cam 43 has passed by the roller 45, the member 46 will be carried upward by the spring 48^a, and the head 48 seated within the recess 49, whereby the plate 22 is checked against movement until the cams shall again assume the positions to allow the arm 27 and plate 17 to move.

It has been previously explained that the centering member 19, which lies to the side of the work, must move out of the way as the work advances toward the feed rolls 21, as otherwise, should the side edge of the work abutted against said stop be irregular or of a slanting nature, such irregularity or slant would, if the centering member 19 remained stationary while the work was passing by, cause a movement of the work out of its previously centered position, and this, of course, would entirely destroy the utility of the centering means.

The stop 19 is in the form of a roller 50 and travels in a slot 50^a on the surface of the table. The roller is carried by an arm 51, to which it is connected by a slot and bolt connection 52, so as to render the roller slightly adjustable. The arm 51 is carried by a pin 53, which extends through the table and is pivotally mounted therein. The portion of the pin below the table has secured thereto an arm 54 carrying a roller 55. This roller 55 is in position to be engaged by the cam surface 56 of a member 57 carried by a rod 58, which rod in turn is connected with the member 22. Thus, the member 57 is moved forward with the forward movement of the plate 22, and the cam surface 56 will engage the roller 55, causing the arm 54 to swing, which in turn will move the arm 51, carrying the roller 52 in the direction of the arrow (Fig. 2) and away from the side of the work, to allow the work to pass freely thereby. By arranging the means for moving the roller 55 so that they are controlled by the movements of the sliding member 22, the roller 55 is moved out of the way in correct timing to the advance of the work.

A spring 59 is employed to pull the arm 54 and its associated parts back to normal position after the work has been fed forward. The work is advanced by the for-

ward movements of the plate or bar 17 into a position between the feed rollers, which have been designated by the general numeral 21. These feed rollers consist of an upper feed roll 60 and a lower feed roll 61, 70 and in the form shown the upper feed roll is provided with a strip of rubber or other frictional material 62. There are two sets of these feed rolls, as will be seen from Fig. 5, both of which are exactly alike in configuration. The feed rolls 60 are mounted upon a shaft 63, and the feed rolls 61 upon a shaft 64. The shaft 64 has positioned thereon, at its end, a gear 65 meshing with a gear 66 on the feed roll 63; and the gear 65 is in mesh with a gear 67 of reduced diameter, which is in mesh with a gear 68 on the cross-shaft 35. Thus, the feed rolls are driven in unison and in opposite directions.

Lying to the outside of each of the feed rolls 60 is a cutting disk 67^a, and lying to the outside of each of the feed rolls 61 is a cutting disk 68^a, one of the disks 67^a and one of the disks 68^a forming in conjunction 90 a cutting mechanism. These disks are arranged in the usual overlapping relation, as shown in Fig. 5, and as the work passes through the feed rolls 60 and 61, the side edges are trimmed by the action of the cutters 67^a and 68^a, so that the surplus material is trimmed therefrom during the feeding operation. It is necessary to perform this trimming operation while the work is still in the position it was placed in when abutted against the members 16 and 19, and by arranging the cutters and feed rolls in the manner specified, the work is delivered directly to the cutter mechanism in its centered position and trimmed in accordance. 100 After the work has been thus trimmed, it is discharged by the rolls 60 and 61 into position to be engaged by the fingers of the reciprocating feed bar 14 and advanced by said feed bar in a step by step movement 110 into position to be acted upon by the shearing mechanism. This portion of the machine and its operation is, however, fully described in the patent of McDonald and Ennes, No. 1,194,728, heretofore referred to 115 and will not be gone into in detail in connection with the present case.

The operation it is thought will be understood from the foregoing, but briefly is as follows: The work is placed with its rear edge abutting against both of the centering members 16 and with its side edge abutting against the centering member 19, and then as the machine operates, the cams 43 and 25 move into position to release the arm 27 and withdraw the head 48 from the recess 49, leaving the movable member 22 free to be carried forward by the action of the spring 24. The forward movement of the member 22 causes the plate 17 to travel for- 130

ward with the work held thereto by the spring fingers 20. As the plate moves forward, the cam surface 56 of the member 57 acts against the roller 55, swinging the arm 54, which swings the arm 51 and moves the roller 50 in the slot 50^a in a direction away from the side edge of the work. Thus, the work passes freely by this centering member and into position between the feed rolls 60 and 61, and by the action of said rolls, it continues to move in a forward direction toward the shearing mechanism, the side trimmers 67^a and 68^a cutting the surplus material from the sides of the work as it passes through the feeding rolls. After having passed through these rolls, it is delivered in position to be taken up and further advanced in a step by step movement by the action of the reciprocating bar 14, 20 and during such step by step movement is cut into scroll-edged blanks.

I claim:

1. In a machine of the class described, the combination of shearing mechanism, means for feeding the work into position to be acted upon by said shearing mechanism, means for positioning the work previous to the feeding operation, means for gripping and carrying the work forward in such position to a point where it is acted upon by the feeding mechanism, and means for locking the movement of the mechanism for carrying the work to the feeding means at other than a predetermined time, substantially as described.
2. In a machine of the class described, the combination of shearing mechanism, means for feeding the work in position to be acted upon by the shearing mechanism, centering members for positioning the work previous to the feeding operation, means for carrying the work forward in such centered condition into position to be acted upon by the feeding mechanism, tension mechanism for operating said work carrying means in one direction, and means for locking the work carrying means against movement at other than a predetermined time, substantially as described.
3. In a machine of the class described, the combination of shearing mechanism, means for feeding the work in position to be acted upon by the shearing mechanism, centering members for positioning the work previous to the feeding operation, means for carrying the work forward in such centered condition into position to be acted upon by the feeding mechanism, tension mechanism for operating said work carrying means in one direction, means for locking the work carrying means against movement at other than a predetermined time, and cam mechanism controlling the operation of said locking means, substantially as described.
4. In a machine of the class described,

the combination of a fixed table, cutting mechanism supported by the table, means movable with respect to the table for carrying the work into position to be operated upon by the cutting mechanism, centering means on the table, centering means on the carrying means, said work being abutted against said centering means previous to the carrying operation and centered thereby previous to movement of the carrying means, and means for moving the centering means on the table out from the path of travel of the work when the carrying member begins its movement and maintaining said centering means out of contact with the work during the entire carrying movement, substantially as described.

5. In a machine of the class described, the combination of a fixed table, cutting mechanism on the table, means movable with respect to the table for carrying the work into position to be operated upon by the cutting mechanism, gage members on the carrying means for the rear end of the work, a gage member for one side edge of the work mounted in the table, said work being abutted against said gage members previous to the carrying operation, and means for moving the gage for the side edge of the work out of the path of travel of the work at the commencement of the carrying movement and maintaining it out of engagement with the work during the entire carrying movement, substantially as described.

6. In a machine of the class described, the combination of a fixed table, feeding rolls on the table, side trimming cutters associated with said feeding rolls, a movable bar-like member in front of said feeding rolls, 105 gage means for the rear edge of the work carried by said bar-like member, spring-grip work holder means carried by said bar-like member and engaging and gripping the work as the latter is placed against the 110 gage means, means for moving said bar-like member to bring the work held by the holder means into the bite of the feeding rolls, said holder means having a less gripping power than the feeding rolls, and said 115 feeding rolls acting solely to release the work from the holding means, whereby the work is delivered to the feeding rolls in the same position it assumed when gaged against the bar-like member, substantially 120 as described.

7. In a machine of the class described, the combination of a fixed table, cutting mechanism supported by the table, means movable with respect to the table for carrying the work into position to be operated upon by the cutting mechanism, a gage member on the table for a side edge of the work and against which the work is placed previous to the carrying operation, and means 130
